SHOWER ASSEMBLY FOR PAPERMAKING MACHINES

Oscar E. Larson, Andover, Mass., assignor to John W. Bolton & Sons, Inc., Lawrence, Mass., a corporation of Massachusetts

Application November 21, 1945, Serial No. 630,033

2 Claims. (Cl. 299—59)

1

This invention relates to washing devices which are known as "shower pipes" such as are used for washing or cleaning strainers, felts, etc., in paper and pulp mills. It is particularly adapted for cleaning shower pipes similar to those shown in the patent to Witham, Shower pipe, August 28, 1934, No. 1,972,001, and such as shown in patent to Schueler, Shower pipe cleaning device, May 19, 1942, No. 2,833,768, and those shown in the patent to Paramor, Washing device comprising shower pipes, April 16, 1935, No. 1,997,651.

In this class of shower pipes there is a longitudinal pipe with a plurality of openings, nozzles or what amount to spray outlets spaced longitudinally, there is always an inlet pipe and there may be an outlet pipe although in some cases the shower pipe comes to a dead end.

In some cases, projecting nozzles are used, in other cases radial cylindrical holes are used and in the case of Witham, there are aligned orifices which connect on the outside with one groove and on the inside with another groove.

As the stock contains a good deal of solid material, it is necessary that these nozzles, holes or orifices should be cleaned from time to time and it is desirable that the liquid which flows through them should be spread out in fan shape.

It is also desirable that the cleaning device should not obstruct the flow of water to any extent.

Schueler shows power means for rotating an axially disposed rod carried by suitable bearings in the shower pipe and carrying a plurality of cleaning members one for each spray outlet, such cleaning members preferably being flexible such as brushes, in such a position that each can sweep through an inside groove angularly disposed to the axis of the shower pipe. That angle is preferably 80°, the movement of each brush and the position of the inside groove being in a plane at an 80° angle to the axis of the pipe and of the rod.

Whether with this arrangement of flexible members, such as brushes, flexible rubber members or scrapers, and whether operating in such grooves or merely passing along the inside of spray outlet holes of a cylindrical shape which holes pass through the wall of the shower pipe, or spray outlet holes which are flush with the inside wall of the shower pipe but diverge on the outside, there is a tendency for the solid particles of the liquid being sprayed to gradually build up around and near the inside end of each spray outlet hole with the result that when disturbed by a cleaning member these solid particles tend to bunch and to clog the outlet and in fact the whole pipe.

To make the whole line of spray even, the outside groove of the Witham nozzle or a baffle, when used, should be at an angle of five to ten degrees from the axial line so that the separate sprays

2

overlap, or the nozzles could be staggered or offset in parallel lines.

I use an outlet with a flushing valve turnable by an operating rod which also carries the nozzle cleaning members.

5 The purpose of this device is to more thoroughly clean a shower pipe which has an inlet pipe at one end, aligned spray outlets of any one of the various kinds, and which has an outlet pipe. I accomplish this by providing a rod which rod also carries the spray outlet cleaning members.

10 The parts are so arranged that when the rod is turned from the outside, either manually or by power to cause the cleaning members to sweep past the inside ends of the spray outlets, the outlet flushing valve is fully opened by the rod with the result that there is a great rush of water through the shower pipe and through the outlet flushing valve which carries with it the loosened solid material.

15 For normal running the operating rod is so turned that the cleaning members are moved from the inside ends of these outlets and at the same time the flushing valve is closed.

20 25 The advantages of my turnable construction are that it is compact, the operator makes only a turning motion, instead of pulling and turning, and if the flushing valve is left open, the spray is so reduced that it is a signal to the operator to close that valve.

25 30 The port or ports in the fixed flushing valve casing and the port or ports in the turnable plug should be so positioned that they register and thus open the valve when the flexible members 35 are sweeping past the spray outlets or at any rate are closed while these spray outlets are unobstructed during most of the time. To assist this, there is preferably a stop or there are stops 40 which compel the axial operating rod to stop in its turning movement when the flushing valve is closed and the spray nozzles are wide open.

35 40 In the drawings Fig. 1 is a diagrammatic elevation partly in section of a shower pipe of my construction in place over the wire of a Fourdrinier paper making machine.

45 Fig. 2 is a sectional view as on line 2—2 of Fig. 1, showing one construction of my flushing valve.

50 Fig. 3 shows part of a section of a shower pipe with my preferred form of nozzles in the preferred arrangement.

55 Fig. 4 is a view similar to Fig. 3, showing another type of nozzles in a staggered arrangement.

Fig. 5 is a sectional view similar to Fig. 2 on the line 5—5 of Fig. 8, showing a flushing valve with two instead of one set of valve ports but the centralizer T omitted.

60 Fig. 6 is a view similar to Fig. 5, showing another type of flexible cleaning member and its

association with a flushing valve of the type shown in Figs. 10, 11 and 12.

Fig. 7 is another view similar to Figs. 5 and 6 of still another type of cleaning member.

Fig. 8 is an enlarged vertically longitudinal sectional view of the end of a shower pipe where the flushing valve is located, the valve being of the type shown in Figs. 2 and 5.

Fig. 9 is a vertical sectional elevation of the handle end or end opposite to the flushing valve of a shower pipe such as is shown in Fig. 1.

Fig. 10 is a vertical sectional elevation of another type of valve from what is shown in Figs. 5 and 8, being such as shown in Fig. 6, part of the handle end of the shower pipe being shown in elevation.

Fig. 11 is an elevation of the end of the plug member disk of a plug such as shown in Fig. 10, removed from the shower pipe.

Fig. 12 is an elevation showing the end of the nipple part of a flushing valve such as shown in Fig. 10.

In the drawings, Fig. 1 shows one use of a shower in a Fourdrinier machine in a paper mill, 4 representing the wire pit and 5 the Fourdrinier wire.

In this construction, the shower pipe such as A is shown as having outlets or nozzles N at the bottom so as to spray the wire 5 but in numerous other paper making machines in a paper mill, the shower pipe nozzles or outlets are at the top instead of at the bottom.

In Figs. 1, 2, 3, 5, and 8, there are shown nozzles of the removable type like those in patent to Witham, "Shower Pipe," August 28, 1934, No. 1,972,001. Each of these nozzles indicated by N has a central hole 1, an outside groove 2 and an inside groove 3.

As shown in Fig. 3, the outside grooves 2 are preferably arranged so as to make an angle of from five to ten degrees with the axis of the shower pipe so that the sprays will not strike each other but will overlap as shown in Fig. 1.

I represents an inlet water pipe with a shut off valve 90 and O represents an outlet water pipe with a shut off valve 91 and F represents a flushing valve which is positioned between the end of the shower pipe A and the beginning of the outlet pipe O.

As shown, there is an elbow 17 between the end of shower pipe A and outlet O. The valve member 10 is shown as a nipple threaded into this elbow 17, and there is also a coupling 18 which connects member 10 with the shower pipe A in the conical valve construction F shown in Figs. 1, 2, 5, 8.

In the other type of valve V shown in Figs. 6, 10, 11, and 12, there is a similar arrangement with the valve member or nipple 20 threaded into a coupling 18 and elbow 17.

Valve F is carried by the end of an outlet cleaning rod R which as shown in Figs. 1, 2 and 5 to 9, also carries a series of cleaning members shown in Figs. 1, 2, 5 and 8, as brushes B of such a character as to permit water to pass them, each being positioned close to a nozzle N in a position so that when rod R is turned each brush B will sweep through the inside groove 3 in the adjoining nozzle N or past a spray outlet of any other type.

The flushing valve F includes a fixed member 10 which is hollow and as shown, is of truncated conical form with two outlet ports 11 and 11 communicating with the outlet pipe O and a turnable plug 12 having inlet ports 13 and 13 communicating with the shower pipe A, these ports

11 and 13 being of such a character that when they register so as to open the flushing valve F, the water can rush through them from the inlet pipe I through shower pipe A and out through the outlet pipe O, preferably with such force and with such volume that it carries along all of the sediment which is loosened by the turning or reciprocating motion of rod R and the brushes such as B, thereby cleaning the spray nozzles such as N.

The plug 12 is held in close contact with the member 10 by rod R which is held in axial position by means of a collar 14 carried by the rod R and held in adjusted position by means of gland G as see Fig. 9.

In Fig. 4 is shown a shower pipe C with nozzles 7 which may be of any shape but are staggered in zig-zag form in two rows or lines.

As shown in Fig. 2, there may be only one outlet port 11 and one inlet port 13.

In long shower pipes, I may use one or more centralizers or steady supports T such as shown in Fig. 8. As shown, each support T is fixed to a rod by a pin 61 and has three arms through each of which is a large hole 60 to allow free passage of the water.

In Figs. 6, 10, 11 and 12, I show a shower pipe D with a rod K which carries a number of flexible members 28 each held in a position to sweep past a nozzle such as 8 which, as shown, is of cylindrical shape.

Rod K also carries at its end the plug member 23 of a valve V, which, as shown, includes a nipple 20 through which are stationary valve ports 21, 21 which allow water to pass from coupling 18 to elbow 17 and therefore to outlet pipe O.

Plug member 23 includes a two part disk 19 which engages nipple 20 and has inlet ports 24, 24. Ports 24 and 21 should register when members 28 are passing nozzles such as 8. The face of disk 19 which is not in contact with nipple 20 can be flat or its rim 29 can be beveled to prevent clogging and the shape and edges of any of the valve ports can be varied in many ways.

The plug member 23 is carried by rod K through which is a pin 25 which enters the slots 26, 26 in the plug member 23, there being a compression spring 27 which tends to keep the disk 19 of plug member 23 in engagement with the nipple 20, the whole rod K being turnable, as is the rod R, so that the ports 21 and 24 of the valve V can be kept closed most of the time with the flexible members 28 away from the nozzles 8 but the valve can be opened with the ports registering during the whole or part of the time when the flexible members 28 are sweeping past the nozzles 8 for cleaning.

As shown in Fig. 7, a rod such as H, in place of the flexible members 28, can carry blades such as 30 each of which, when the rod is turned, scrapes along the inside of the shower pipe L, sweeping past the small inner end of one of the outwardly flaring or tapered nozzle holes 9 at the top.

In every construction there is preferably a gland G which includes a member 50, threaded into a T 51, which contains packing 52 with a packing nut 53 and over this there is preferably a cap 54.

As the brushes B should be in relatively fixed axial position so that they will always sweep through channels such as 3, preferably I use an inside collar 14 adjustable on rod R by a set screw 55 so that collar 14 rests against the end of member 50 of gland G.

On the outer end of cap 54 I use an outside

collar 56 adjustable on rod R by a set screw 57 so that it can rest against the outside end of cap 54.

As the brushes or other flexible members have a certain amount of width, when and if it is necessary to make the tapered contact between the members 10 and 12 of the tapered valve F closer as they wear, they can both be adjusted and the valve kept tight while in the construction of valve V, the spring 27 keeps the valve members together at all times without adjustment.

In all cases I prefer an inside collar 14 and an outside collar 56 to keep the brushes in position to pass and clean nozzles N, 7, 8, or 9. Collar 14 also keeps the valve members in contact.

As it may be desirable to provide a stop by means of which the workmen can know when there is a flow of spray through the nozzles but nothing flowing through the flush valve, I can provide a stop arm 58 on the outside of collar 56 and a stop 59 on the outside of cap 54, which is so made that it can slide on axially but cannot turn with reference to T 51 and the shower pipe. See Figs. 1 and 10.

By loosening set screw 57 and by turning the outside collar 56 stop arm 58 can be so set that when it engages the stop 59, the flushing valve ports will be entirely open or partly open or entirely closed so that the workmen can turn the handle 42 in one direction until it stops for flushing, or for closing the flushing valve, with the cleaning brushes in position so that they will not obstruct the spray nozzles like N, 7, 8, or 9.

As valve members such as 10 or 20 are threaded, they can be so turned as to permit full or partial registration with the ports in the valve plug member when a stop arm 58 engages a stop 59 if it seems desirable to reduce the flow of the flushing water.

I claim:

1. In combination in a shower device for paper making machines, a shower pipe provided with a plurality of spray outlets spaced longitudinally thereof, a water inlet pipe connected to one end of the shower pipe and a water outlet pipe connected to the other end thereof, a cleaner for the shower pipe including a rod disposed axially within the shower pipe, means mounting said rod for turning movement and preventing axial movement thereof, a flush valve adjacent the outlet end of the shower pipe and including a valve seat and a valve member having ports adapted to be brought into and out of reg-

istration to open and close the valve, said valve member being connected to said rod for operation by turning movement of the latter, said rod being provided with means extending to the exterior of the shower pipe and the water inlet pipe and operable to impart a turning movement to the rod, and a plurality of cleaning members carried by said rod, the cleaning members being circumferentially proximate to the spray outlets and adapted to sweep over the same when the rod is turned to open the valve, the cleaning members and the valve member being connected to the rod in such relation that the opening of the valve by only turning the rod brings the cleaning members into engagement with all the spray outlets.

2. In combination in a shower device for paper making machines, a shower pipe provided with a plurality of spray outlets spaced longitudinally thereof, a water inlet pipe connected to one end of the shower pipe and a water outlet pipe connected to the other end thereof, a cleaner for the shower pipe including a rod disposed axially within the shower pipe, means mounting said rod for turning movement and preventing axial movement thereof, a flush valve adjacent the outlet end of the shower pipe, said valve being connected to said rod for operation by turning movement of the latter, said rod being provided with means extending to the exterior of the shower pipe and the water inlet pipe and operable to impart a turning movement to the rod, and a plurality of cleaning members carried by said rod, the cleaning members being circumferentially proximate to the spray outlets and adapted to sweep over the same when the rod is turned to open the valve, the cleaning members and the valve being connected to the rod in such relation that the opening of the valve by only turning the rod brings the cleaning members into engagement with all the spray outlets.

OSCAR E. LARSON.
